UNITED STATES PATENT OFFICE.

MARVIN H. JESTER, OF DENVER, COLORADO.

CLIP FOR SECURING PLASTER-BOARDS TO METAL STUDDING IN HOLLOW-PARTITION CONSTRUCTION.

1,258,906.

Specification of Letters Patent. Patented Mar. 12, 1918.

Application filed November 17, 1914. Serial No. 872,573.

To all whom it may concern:

Be it known that I, MARVIN H. JESTER, a citizen of the United States of America, residing at the city and county of Denver and State of Colorado, have invented a new and useful Clip for Securing Plaster-Boards to Metal Studding in Hollow-Partition Construction, of which the following is a specification.

10 My invention relates to a new metallic clip for the construction of metallic studding hollow wall plaster board partitions that are adapted to receive and support mortars, cements, and stucco plastering materials, and the objects of my invention are:

First, to provide a metallic clip that will support on opposite sides of metallic studding, parallel rows of plaster boards or cement blocks in such a manner as to form a hollow plaster board partition.

Second, to provide a metallic clip that will enable a hollow partition to be constructed of plaster boards and will enable the plaster boards to be set up in broken jointed relation to each other, and that provides plaster receiving and supporting surfaces on each side of the hollow space in the partition.

And

Third, to provide a hollow wall and partition clip that is arranged to support plaster boards and secure them to the metallic studs without the use of clamping or binding nails, keys, or wedges.

I attain these objects by the mechanism illustrated in the accompanying drawings, in which:

Figure 1 is a front view illustrating the manner of securing plaster boards to metal channel studs, by means of the preferred form of the improved clip.

Fig. 2 is a perspective view—full size—of a pair of clips arranged as in use, a stud being shown in dotted lines extending through the said clips.

Fig. 3 is a horizontal sectional view of a portion of a partition, showing how the clips fit around the stud and support oppositely positioned plaster boards.

Fig. 4 is a vertical sectional view through

a portion of a partition, showing a pair of 50 clips arranged as in Fig. 2.

Fig. 5 is a vertical sectional view on a slightly smaller scale, of the portions of a partition adjoining the ceiling and floor and showing the manner of securing the top and 55 bottom clips to the ceiling and floor respectively, in order to support the metal stud.

Fig. 6 is a perspective view of a modified form of the clip shown in Figs. 1 to 5.

Fig. 7 is a face view showing the manner 60 of securing plaster boards to studding by means of the modified form of clip.

Fig. 8 is a vertical sectional view of a portion of a partition, showing the application of the clip in constructing a solid 65 partition.

Fig. 9 is a similar view showing the clips arranged in pairs, as in the construction of hollow partitions.

Fig. 10 is a horizontal sectional view illustrating more clearly the manner in which the clip is secured upon the stud, and the 70 plaster board supported by the clip.

Fig. 11 is a vertical sectional view illustrating a hollow outside wall embodying the 75 employment of the form of clip shown in Figs. 1 to 5.

Fig. 12 is a top edge view showing the studding and plaster boards of a hollow partition and an arrangement of the clips 80 illustrating how they may be used independently of the studding, or at any intermediate point between two studs, in order to connect the adjoining ends of plaster boards.

Fig. 13 is a perspective view of the clip 85 shown in Fig. 10, showing the stud-engaging portion bent down.

Similar characters of reference refer to similar parts throughout the several views.

Referring to the drawings:
The numeral 1 designates a channel-like clip embodying my invention. This clip consists in particular of a flat central stud-receiving portion 2, the opposite edges of which terminate in vertical side portions 3, 95 which terminate in horizontal laterally extending portions 4, which in turn, terminate in outer vertical side members 5, the mem-

bers 3 and 5 being far enough apart to fit snugly over the corner edges of plaster boards of the required thickness, and for partitions of the generally used heights the 5 clips are preferably made of #20 gage galvanized sheet iron or steel, to prevent rusting action, although they may be made if desired of thin galvanized metal for low ceiling partitions, and of thicker metal for 10 high ceiling partitions.

The improved metallic clip is bent into channel shapes that are formed to enable the clip to be easily and quickly placed around the metal studding in the construction 15 of plastered partition walls in buildings.

Each clip is preferably made about two inches long for the general hollow partition construction work, but can be made longer 20 or shorter if desired, and where thick plaster cement or concrete blocks are used for walls, they may be made of any desired length and breadth and of much thicker metal.

My invention contemplates the use of my 25 improved clip with any suitable form of cross section of metal studding, but it has been especially and particularly desired to be used with metallic studding in the form of channel bars. I have employed both flat 30 and channel bar studding in my former clip constructions, as is evidenced in numerous patents issued to me in this art within the past three years, particularly in Patents Number 1,001,146, and 1,078,144, which were 35 issued to me August 22, 1911, and November 11, 1913, respectively; and in all constructions where metallic studding is used in place of the old commonly used wooden studs it is to be understood that the metal 40 studs extend from the floors or floor-beams to the ceilings or ceiling-beams of the different floors of buildings, and it is necessary that the opposite ends of the metallic studs be secured firmly and rigidly to the floors 45 and ceiling members at their predetermined set distances apart and against accidental displacement.

This has often been accomplished in past 50 constructions by bending the ends of the studding at right angles to their vertical positions and securing them by bolts, nails, screws, or other suitable means to the floors and ceiling beams. My present clip, however, is especially adapted to secure the ends 55 of the metallic studs to the floor and ceiling beams without bending or otherwise securing their ends to them, as will be fully explained hereinafter.

The flat plate shaped central body portion 60 of the clip is made a little wider than the width of the metal stud the clip is to be used with. Thus if a three-quarters inch wide channel stud is used, the central body portion is made preferably just enough

wider to allow the metal in the clip to be 65 bent at right angles to this flat central body portion to form the inner side plates 3 of the body portion of the clip.

These side plates 3 extend along the opposite edges of the channel bar 6 a short 70 distance, preferably a distance of about five-eighths of an inch, and they form between them and the underside of the body portion, a channel shaped space through which the channel bar extends loosely between the 75 side plates 3 and through an aperture 7 formed through the body portion of the clip to receive it.

My improved clip is made to be instantly 80 and quickly placed on and around the channel bar stud by workmen to receive the ends of the plaster boards as they are laid up against the channel studs, and they are adapted to secure the plaster boards to the opposite sides of the studs with a strong in- 85 closing channel form of support that holds them rigidly in vertical and horizontal alignment across a room and from floor to ceiling.

My improved clip is made to stand in a 90 horizontal plane across the vertical plane position of the channel bars between the floor and ceiling, and as they are set to stand edgewise across the length of a partition with their wide sides at right angles to 95 the lengthwise line of the partition, the aperture 7 in the body of the clip through which the stud passes, is arranged at right angles to the length of this body portion, and in order that the clips may be placed 100 on the channel bars after they are secured in place at any part of their length between the floor and ceiling, the central body portion of the clip is provided with an inlet slot 8 that extends into one end of it to the 105 transversely positioned channel bar receiving slot 7. This inlet slot is arranged along one edge of the body portion of the clip, and it enables one end of the clip to be hooked around one of the flanges of the 110 channel bar, and then to be swung around so the aperture in the clip fits around the channel bar and the edge 9 of the aperture 7 of the clip fits against the flat straight side 115 of the channel bar.

The two opposite channel side portions 3 and 5 of the clip then extend parallel with the opposite sides of the channel bar, and the corner edges of the plaster boards 10 are simply set into these channel grooves, 120 which are made of a width to fit snugly but easily over the plaster boards.

It requires, however, two clips positioned in opposite relations to each other and placed one on top of the other back to back, 125 as shown in Fig. 2, the clips that receive and fit over the lower corner edges of each plaster board having their channel grooves

opening upward, and those that receive and fit over the upper corner edges of the boards having their channel grooves facing downward when the clips are on the channel studs. Consequently the clips are used in pairs between the two clips that secure the opposite ends of the channel bars to the floors and ceilings.

My improved clip makes hollow partitions that are from two and one-half inches and more in thickness when plastered on both sides.

In Figs. 6 to 10 I illustrate a modification of the clip shown in the other figures. 15 In this modification a clip is produced that only partially surrounds the channel bar, and it provides channel grooved ends 11, that support the plaster boards on one side of the channel bar only. Consequently it 20 can be used for a single sided plaster board partition, and in order to make a hollow partition of them, it is necessary to use two of them placed opposite each other on the channel bar and projecting from opposite 25 sides of the channel bar.

This modified form of clip comprises a central body portion that consists of a flat plate portion 12, in which a T-shaped slot 13 is formed, that enables the clip to be 30 easily and quickly hooked over and swung around on the channel bar in position to receive the ends of the plaster boards.

On the opposite side of this central body portion from the T-shaped slot, a portion of 35 the central body portion is turned down at right angles to form a flange portion 14, that acts to truss the central body portion and also that is adapted to extend over the outside of the plaster boards.

40 From the opposite ends of this central body portion, the two channel ends 11 are formed, that project from the central body portion of the clip in the opposite direction from the truss flange 14. Consequently the 45 channel members project from one side of the central body portion and the truss flange from the other. The inside and outside edges of the T-shaped slot are positioned to bring the flat side of the channel bar far 50 enough into the plane of the two sides to allow the plaster boards when they are inserted in the channel ends to bear against the channel bar, and the channel bar receiving slot is made of a width to fit the 55 channel bar and to allow it to abut against its outer edge 25 when the plaster board bears against the channel bar.

These modified shapes of clips can be applied instantly to any part of the channel bar. It requires two of them arranged in 60 opposite relation to each other for a double board hollow partition.

These hollow wall and partition constructing clips can be used for outside hollow

walls, where it is desired to use cement or 65 plaster blocks or large bricks, as shown in Fig. 11, where a 9 inch wall is illustrated showing my clip applied to a wide channel bar or beam 16.

The essential elements of my invention 70 are that fire-proof, dampness-proof outside surface or inside partition walls of great strength and rigidity can be constructed cheaper of metal and plaster board or cement than of wood or of brick and mortar 75 construction, as this form of clip enables a good many more square yards of it to be erected in any given time than can be laid or put up of the other constructions.

While in the foregoing, the clip has been 80 described as being secured to the studs by means of the slots 7 and 8, it is obvious that the clip may also be used independently of the studs at any intermediate point between any two studs, where, for any reason, 85 the joint between the adjoining ends of two plaster boards occurs at intermediate points between the studs, as by the employment of short lengths of boards to fit in spaces less than the standard length 90 of the boards used. Fig. 12 illustrates how the clips may be used as above indicated. At A the clips are shown secured to the studs and to the plaster board, the joints occurring at the studs. At B the joints of 95 the opposite boards occur on one side of the stud, and the clip is shown abutting against the stud, and clamped over the ends of the boards. At C the clip is shown at an intermediate point between the two studs, where 100 two boards of less than standard length are used.

It will thus be seen that the clip may be used to clamp the boards at intermediate points between the studs, and when so used 105 the form of clip shown in Fig. 2 may be employed.

The operation of using my clip in the erection of a partition is as follows:

The workman places the clips along the 110 floor line and also along the ceiling line of a partition at some predetermined distance apart that will take the preferred size of plaster board they wish to use. In my practice of erecting these partitions I preferably use a plaster board that is about 5/16ths 115 of an inch thick, and that is 18 inches wide by 32 inches long. These clips are spaced along the floor and ceiling lines 16 inches apart between centers, and they are positioned with their channel grooves facing upward, while the ceiling clips are positioned with their channel grooves projecting downward, and they are nailed directly to the floor and ceiling beams or are secured by 120 nails along their sides and ends, whichever way is most convenient. The channel bars are then cut to a length that will allow them 125

to be sprung into the channel receiving apertures of these floor and ceiling clips, which is very quickly done. Having erected the metallic studding channel bars along a line of partition, the workman takes a plaster board and inserts its lower edges in the upturned channel members of the floor clip, and with the opposite ends of the plaster board at the center of the two channel bars, 10 the plaster board is to rest against. Then on top of the upper edge of this plaster board he places two clips, one around each channel bar, with their channel grooves outward, and presses them down over the edges 15 of the plaster board. He then takes two more clips and places them directly on top of the clips that he has just placed on the top edge of the plaster board, placing them of course on the channel bar first. He then 20 takes another plaster board and inserts its lower edges in the up-turned channels of the last two clips. Then on the upper edges of this second plaster board he repeats the operation of placing a pair of clips around 25 the channel and on the top edges of the second plaster board, and the upper clips of this second pair are ready to receive the lower edges of another plaster board. In this way one workman can put up a good 30 many square yards of plaster board in a very short time, and as soon as they are up they are ready to receive the mortar of the plastering material.

My improved clips do not need any nails, 35 wedges or clamping devices of any kind, and they provide a very rigid strong hollow partition that is dust-proof, vermin-proof, fire-proof, and sound proof, and that can be erected much cheaper than the wooden partitions at present in use.

Having described my invention, what I 40 claim as new and desire to secure by Letters Patent, is:

1. A hollow metal stud wall or partition 45 construction clip comprising a metal plate having a central channel shaped portion provided with an aperture and having a longitudinal slot extending from one edge to said aperture adapted to permit said clip 50 to be mounted on a metal stud at any part of its length, said central portion having opposite side portions formed with channeled grooves in them arranged to receive the corner portions of plaster boards or cement blocks.

2. A plaster board metal channel bar stud 55 hollow wall or partition construction clip comprising a flat piece of metal provided with an aperture through it and a slot at 60 one end intersecting said aperture arranged to permit it to be hooked onto and swung around and securely locked to said metallic channel bar stud, said piece of metal being provided with oppositely arranged project-

ing plaster board inclosing members, said 65 plaster board inclosing members being arranged to support and secure the opposite corner portions of plaster boards or cement blocks to the opposite sides of said channel bar stud in parallel rows with a hollow space between them. 70

3. In a device of the character described, the combination with a stud, of a clip having a horizontal member provided with a stud-receiving slot and a slot-extending 75 therefrom through one end of said horizontal member, said horizontal member having extensions which are bent to form parallel U-shaped channels which lie on opposite sides of said stud. 80

4. In a device of the character described, the combination with a stud, of a clip for securing plaster boards thereto, consisting of a metal plate bent to form a central 85 U-shaped member, and side members which form in conjunction with the sides of the U-shaped member, parallel channels, the horizontal part of the U-shaped member having a slot to receive said stud, and an entrance slot extending therefrom through 90 one end of said horizontal part.

5. In a device of the character described, the combination with a stud, of a clip for securing plaster boards thereto, consisting of a metal plate bent to form three parallel 95 U-shaped members, the sides of the central member forming the inner sides of the outside members, the horizontal part of said inner member having a stud-receiving slot and a slot leading therefrom through one 100 end of said horizontal part.

6. A metal clip for constructing hollow walls or partitions of plaster composition, 105 boards or blocks, said clip comprising an apertured central body portion provided with a slot extending from one edge to said aperture and with opposite portions arranged and adapted to fit over the edges of said boards or blocks and hold them in parallel rows and spaced at a short distance 110 apart, a second clip of similar construction placed in inverted order above the first clip, said clips being adapted to support said boards or blocks in an even line or in any staggard joint arrangement at which the 115 boards of one side of the partition or wall may happen to come, independently of those of the other side.

7. In a hollow wall or partition, metal 120 studding, plaster board or cement block construction, a metal clip, comprising an apertured central body portion provided with a slot extending from one edge to said aperture and with opposite portions arranged and adapted to fit over the edges of said 125 boards or blocks and hold them in parallel rows, spaced at a short distance apart, a second clip of similar construction placed in

inverted order above the first clip, said clips being adapted to support said boards or blocks in an even line or in any staggard joint arrangement at which the boards of 5 one side of the partition or wall may happen to come, independently of those on the other side said clips being arranged to support two rows of boards or blocks independent

of and at any part of the distance between the metal studding. 10

In testimony whereof I affix my signature in presence of two witnesses.
